UNITED STATES PATENT OFFICE.

KATHERINE V. MINEHART, OF GERMANTOWN, PENNSYLVANIA.

BAG-HOLDER.

1,121,525.

Specification of Letters Patent. Patented Dec. 15, 1914.

Application filed December 24, 1913. Serial No. 808,606.

To all whom it may concern:

Be it known that I, KATHERINE V. MINEHART, a citizen of the United States, residing at Germantown, in the county of Philadelphia and State of Pennsylvania, have invented new and useful Improvements in Bag-Holders, of which the following is a specification.

This invention relates to strainers for culinary purposes in general, as well as for other work of a like character, and it resides, primarily, in the provision of an improved holder for the bag or other straining or filtering device, which may be manufactured at a low cost and which is so constructed and arranged as to support the afore-mentioned device firmly in place over the pan, kettle or other receptacle for the strained or filtered substance at a distance from the edge thereof, thus avoiding the danger of spilling present in many of the strainers now in use.

An embodiment of the invention is illustrated in the accompanying drawing, whereof—

Figures 1 and 2 are, respectively, a perspective view of the improved strainer, complete, and an enlarged, fragmental, vertical section on line 2—2, Fig. 1.

Referring more particularly to said drawing, A indicates the straining device proper, and B the holder therefor. The former part or element is here shown as constituted by a bag 5 of suitable size and shape and made of any desired textile or other material. It is designed to contain the substance to be strained, as will be understood, and is provided at its upper edge with a continuous hem 6, through which a strengthening wire 7, or the like, is passed.

The holder B for the bag is preferably constructed from a single resilient element which, in the present instance consists of two strands of wire arranged side by side. The central portions of these strands are twisted together and bent to form a ring 8, the two double strands being united and twisted together beyond said ring to produce a horizontal, radially-arranged projection 9, after which they diverge to form a skeleton handle B'. This handle, as shown, is given substantially the shape of a right triangle, the downwardly-inclined or diagonal portion 10 of the inner strand constituting the hypotenuse thereof, and the outer strand being bent upon itself at right angles to form the other two sides 11 and 12.

The short upper arm 11 of the latter strand is arranged horizontally, and in endwise alinement with the projection 9, forming in effect a continuation thereof and serving to connect the handle with the ring 8, while the long arm 12 is arranged perpendicularly to the first-named arm. The inclined portion 10 and the vertical arm 12 meet at their lower ends, as will be apparent, and are twisted together, the twisted member 13 thus formed being disposed in endwise alinement with the arm just referred to. In this way, a firm and, at the same time, easy grip is insured, since the fingers may be readily passed around the inclined portion 10, and the thumb pressed upon the horizontal arm 11. The inclined portion 10, aside from its function as a complementary part of the handle also serves as a bracing connection between the vertical arm 12 and the horizontal arm provided by the parts 9 and 11 and prevents said horizontal arm from sagging.

At the lower end of the twisted member 13, the strands again diverge, and are bent to form the hereinafter-described clamp B², the said member 13 thus acting as a connection between the latter and the handle. This clamp is preferably produced by leading the divergent portions first horizontally in opposite directions and then upwardly, as indicated by the numerals 14 and 15. The vertical portions 15 are then bent, first inwardly, at 16, and then downwardly at 17, the terminals 18 of the latter portions being finally bent slightly inward. The pairs of bent portions or parts 14 and 15 will, therefore, constitute the outer jaw of the clamp B², and these parts occupy substantially the same plane as the connecting member 13 and handle arm 12. The inner jaw is constituted, in like manner, by the two vertical parts 17, which are disposed directly behind, and in spaced, parallel relation to, the parts 15, and are joined thereto by the inward bends 16, the latter forming, in consequence, not only the connection between the two jaws, but, also, the top of the clamp. The clamp B² engages upon the wall of the receptacle which receives the strained substance from the bag A, the engagement of said clamp with said wall being effected by fitting the clamp over the wall and then pushing the bag holder downwardly as far as the bends 16 will permit and the disengagement of said clamp from said wall being effected by lifting the bag holder away.

from the receptacle. The triangular form of the handle B' specially promotes the fitting of the support upon the kettle or other receptacle and its removal therefrom. In fitting the bag holder, the downward pressure necessary to the operation is applied to the arm 11 and in removing the bag holder, the lifting thereof is facilitated by the fact that the handle has a wedge fit in the hand. 10 The form and relation of the handle is of further advantage in that there is no particular liability of the hand, when gripped about the handle, touching the bag or becoming soiled by the substance adhering to 15 the bag or dripping therefrom.

The ring portion 8 of the holder B is designed to encircle the upper part of the bag or other straining device, as will be understood, and in order to secure the said bag in 20 place, a retainer C is provided. This element consists, as here shown, of an annular, metallic band, ring or hoop 19, the diameter of which is but very little smaller than that of the ring, so as to enable it to fit in the 25 mouth of the bag and to coöperate with said ring in exerting a clamping action upon the material of which the interposed bag is made. The upper edge of the said band is turned over in an outward direction, to form 30 the continuous bead 20 depicted in Fig. 2, between which bead and the ring 8 the strengthened hem 6 of the bag is clamped. It will be seen, therefore, that the mouth of the bag is maintained in open or distended 35 condition by the band 19, and is, also, clamped between the latter and the ring 8 and thus securely attached to the holder B. The said holder, by reason of the construction of its handle and clamp, may be read-

ily applied to or detached from the pan or 40 other receptacle, and, when in place thereon, will dispose the bag over such receptacle and at a distance from the wall thereof, the wires of which the clamp is formed having, 45 preferably, sufficient inherent resilience to enable the clamp to tightly grip said wall. Finally, the band 19 may be easily and quickly removed from the bag, and the latter, in turn, from the holder, so that all parts of the complete device may be thoroughly cleaned when necessary.

I claim:

A holder for straining bags and the like, having at one end thereof a horizontal ring adapted to support the bag and to encircle 55 the mouth thereof, a skeleton handle connected to said ring and embodying a downwardly and outwardly inclined inner member and an angular outer member having a horizontal arm joined at its inner end to the 60 upper end of the inclined member and also to said ring and a vertical arm joined at its lower end to the lower end of said inclined member, and an attaching clamp connected to the lower end of said handle and formed 65 to engage the wall of the vessel which receives the material strained through the bag, the said inclined member forming a bracing connection between said vertical and horizontal arms and preventing the latter from 70 sagging.

In testimony whereof I have hereunto set my hand in presence of two subscribing witnesses.

KATHERINE V. MINEHART.
